UNITED STATES PATENT OFFICE.

WILLIAM H. HARDING, OF PHILADELPHIA, PENNSYLVANIA.

BURNER FOR CEMENT-KILNS, &c.

No. 928,561.

Specification of Letters Patent.

Patented June 29, 1908.

Application filed February 1, 1907. Serial No. 355,222.

To all whom it may concern:

Be it known that I, WILLIAM H. HARDING, a citizen of the United States, residing in Philadelphia, Pennsylvania, have invented 5 certain improvements in Burners for Cement-Kilns, &c., of which the following is a specification.

My invention relates to certain improvements in burners for introducing fuel into a 10 cement kiln.

My invention is particularly adapted for use in connection with a kiln having a cylindrical body portion and a front and rear hood, the rear hood communicating with the 15 stack and the front hood having an opening for the discharge of the clinker.

The object of my invention is to improve the construction of the burner so that the 20 fuel will be introduced under pressure to the kiln in a more thorough manner than heretofore, in order that the flame produced will completely drive off the carbonic acid gas and reduce the material to clinker.

In the accompanying drawing:—Figure 1, 25 is a side view partly in section of a kiln of the rotary type, illustrating my invention as arranged for burning pulverized coal; Fig. 2, is an enlarged sectional view of the burner; Fig. 3, is a transverse sectional view on the line 3—3, Fig. 2; and Figs. 4 and 5, are detail views of modifications of the compressed air nozzle.

A is a cylindrical kiln constructed in the ordinary manner.

B is the front hood.

C is the rear hood or dust chamber on which the stack C' is mounted.

The front hood B is mounted on rails in the usual manner, and the outlet opening of this 40 hood communicates with the clinker pit I.

The cylindrical portion of the kiln is supported by rollers a—a and is driven by any suitable gearing A', one of the gears of which meshes with an annular rack a' secured to the 45 kiln A, as shown.

The kiln is arranged at an inclination in respect to the horizontal and the driving mechanism is so driven that the kiln can be rotated at any speed desired. The particular arrangement of the body of the kiln, as illustrated in the drawings, is fully set forth and claimed in an application for patent filed even date herewith.

In the present instance, I have shown a pit 55 e in the bottom of the rear hood below the

mouth of the kiln and E is a bin for the material. The material is discharged from this bin into the pit prior to its being fed into the kiln. In this manner the material is pre-heated and a certain proportion of the carbonic acid gas is driven off the material before it enters the kiln.

A conveyor e' carries the material from the bin to tubes or troughs e through which the material passes to the pit e. In the bottom 60 of the pit, in the present instance, is a screw conveyor e'', which communicates with an elevator e''' discharging into the trough e leading to the interior of the kiln. This construction is fully set forth and claimed in an application for patent bearing even date herewith, and it will be understood that any suitable means may be used for feeding the material directly into the kiln from the bin, 65 as desired.

D is a primary mixing chamber in which the air and carbonaceous fuel are brought together before being introduced into the kiln.

D' is a secondary mixing chamber connected to the primary mixing chamber D 70 through a tube d which extends from the forward end of the said primary chamber through the rear end of the secondary mixing chamber to a point near the forward end of said chamber, as clearly illustrated in Fig. 2. 75 The tube is supported by spiders d' as shown.

b is a tube which extends from the secondary mixing chamber D' through an opening in the front hood B. At the rear of the chamber D' is a damper d'', which regulates 80 the admission of air at normal temperature to the secondary chamber, the rear of said chamber having perforations for the passage of air.

Projecting through the rear head of the 85 primary chamber D is a pipe F, having a nozzle f. The pipe is preferably screw threaded throughout its entire length and adapted to a screw threaded opening in the rear head d''. On this pipe is a handle f' by 100 which it is turned to regulate the position of the nozzle in respect to the opening in the end of the primary mixer D.

In the end of the pipe F is a stuffing box f' through which passes the pipe F' leading 105 from an air compressor F' or other means for supplying compressed air under high pressure. The rear-head d'' of the primary mixing chamber has a series of perforations therein and a damper d''' is arranged to regulate the 110

flow of air at normal temperature through these openings to the primary mixing chamber.

G is a tube through which the pulverized fuel and air under pressure are introduced into the mixing chamber. This tube is connected, in the present instance, with a fan blower G', which in turn is connected by a flue G² to the clinker pit I so that a volume of heated air is drawn through the flue by the fan and forced through the tube G into the primary mixing chamber. The tube is reduced at g to form a nozzle, as illustrated, and opening into the tube directly above this nozzle is a hopper g², which receives the pulverized fuel from the bin H by means of the conveyer h, which is of the screw type in the present instance, but it will be understood that other types of conveyers may be used, if desired.

The parts of the burner are so proportioned that a large volume of air under comparatively low pressure is admitted with the powdered fuel in the present instance to the primary mixing chamber, and while in this chamber the air and fuel are intimately mixed and carried by the incoming air under high pressure through the tube d into the second mixing chamber. At the same time there is drawn in from the rear of the primary mixing chamber a given quantity of air at normal temperature and when it reaches the forward end of the secondary chamber the mixture is supplied with additional air under normal temperature entering the rear of said secondary mixing chamber. Thus, when the inflammable mixture is introduced into the kiln it is in proper condition to be immediately ignited and to produce a suitable flame for the proper clinkering of the material under treatment.

It will be understood that any suitable nozzle f may be used, either the nozzle, as shown in Fig. 2, with a single opening, or, if desired, a spreading nozzle f² of the type shown in Figs. 4 and 5 may be used.

If desired, the blower G', illustrated in Fig. 1, may be open to the atmosphere, so that air at normal temperature may be drawn into the blower and forced through the pipe G, or

the blower may be connected to a heater instead of with the clinker pit, so that the air introduced into the primary mixing chamber will be preheated.

While my invention has been described particularly in connection with a rotary cement kiln, it will be understood that my improved burner can be used for other purposes without departing from the essential features of the invention.

60

I claim:

1. The combination in a burner of a primary and a secondary mixing chamber, the primary chamber having an outlet tube extending into the secondary chamber so as to terminate adjacent to the forward end thereof, means for admitting air under atmospheric pressure to the rear ends of both chambers, a conduit of relatively large cross section connected to sources of fuel and of low pressure air and entering the forward end of the primary mixing chamber, with a high pressure air pipe entering the rear end of said latter chamber and discharging adjacent to the point of connection of the low pressure air and fuel pipe.

2. The combination in a burner of a primary and a secondary mixing chamber, the primary chamber having an outlet tube extending into the secondary chamber so as to terminate adjacent to the forward end thereof, means for admitting air under atmospheric pressure to the rear ends of both chambers, a conduit of relatively large cross section connected to sources of fuel and of low pressure air and entering the forward end of the primary mixing chamber, with a threaded pipe adjustably entering the rear end of said latter chamber and terminating adjacent to the point of connection of the low pressure air and fuel pipe, and a high pressure air pipe connected to said adjustable pipe.

In testimony whereof, I have signed my name to this specification, in the presence of two subscribing witnesses.

WILLIAM H. HARDING.
